NOSE UNIT FOR HIGH SPEED RAILROAD TRAIN

Ivan L. Joy, 1616 W. 29th St., Topeka, Kans. 66614

Filed Oct. 13, 1969, Ser. No. 19,520

Term of patent 14 years

Int. Cl. D12—03

U.S. Cl. D66—1

FIG. 1 is a frontal perspective view of one side of a nose unit for high speed railroad train, showing my design; and

FIG. 2 is a frontal perspective view showing the other side thereof.

I claim:

The ornamental design for nose unit for high speed railroad train, substantially as shown.
